REFRIGERATING APPARATUS

Jewel C. Chambers, Dayton, Ohio, assignor, by
mesne assignments, to General Motors Cor-
poration, a corporation of Delaware

Application December 27, 1933, Serial No. 704,164

11 Claims. (Cl. 62—6)

This invention relates to the conditioning of air.

It is among the objects of this invention to provide a method and apparatus for conditioning air in which desirable temperature and humidity conditions are maintained notwithstanding variations in the temperature and/or humidity loads placed on the apparatus.

Further objects and advantages of the present invention will be apparent from the following description, reference being had to the accompanying drawings, wherein a preferred form of the present invention is clearly shown.

In the drawings:

Fig. 1 is a horizontal cross-sectional view, somewhat diagrammatic and taken along the line 1—1 of Fig. 2, of an apparatus embodying features of my invention;

Fig. 2 is a vertical cross-sectional view similar to Fig. 1;

Fig. 3 is an enlarged view showing a detail of one form of damper mounting;

Fig. 4 is an end view of a portion of the apparatus shown in Fig. 3; and

Fig. 5 is a view of a detail of the form of damper mounting for dampers not directly connected to motors.

In practicing my invention, air is supplied to an enclosure 10, the air being conditioned to produce the desired temperature and relative humidity conditions in the enclosure 10. This is accomplished by causing a stream of air to flow through a plurality of air modifying zones or units 11 and 12 and in varying the character of flow through these zones or units and/or the air modifying intensity of the units so that the desired temperature and humidity conditions are produced in the enclosure 10.

The two or more zones or units 11 and 12 are so arranged with respect to each other that air may flow through these units partly or wholly in a series relation, partly or wholly in a parallel relation or with a varying proportion of the stream flowing in series relation and another portion flowing in parallel relation. To this end, the zones or units 11 and 12 are preferably arranged in a staggered relationship as shown in Fig. 1, with one of the units, in this case 11, nearer the enclosure 10 than the other of the units. The means for varying the character of flow of air through the units may take the form of damper means comprising a set of dampers 13, 14, 15 and 16 operatively linked together so that they may assume various positions as indicated in full and dotted lines in Fig. 1. When the damp-

ers have the position shown in full lines in Fig. 1, the nature of the flow of air is substantially wholly a series flow. When they assume the position indicated by the letter *a*, the nature of the flow is partly in series and partly in parallel. And when the position of the dampers is that indicated by letters *b*, the flow of air through the units is substantially a parallel one. That is, one in which the various portions of the air stream flowing through the zones or units do not pass through both zones or units.

The means by which the dampers are caused to assume the various positions are hereinafter more fully described.

The zones or units 11 and 12 may be air modifying units such as air cooling coils in which a volatile refrigerant is evaporated. Thus they may form portions of a mechanical refrigerating system in which a volatile refrigerant is compressed in the compressor 25, is condensed in the condenser 26, flows in liquid form through the liquid refrigerant line 17 past the automatic expansion valves 18 and 19, is evaporated in the coils 11 and 12, the refrigerant flowing through the coils in parallel relationship, and returning through the evaporated refrigerant line 20 to the compressor 25. The automatic expansion valves 18 and 19 may be controlled by thermostatic bulbs 21 and 22 respectively to maintain the coils in a substantially flooded condition as will readily be understood by those skilled in the art.

The nature of the load on the air conditioning apparatus varies from time to time with respect to the requirements for dehydration and cooling of the air. Means are provided to compensate for these variations. This is accomplished by varying the nature of the flow of air through the air conditioning apparatus in the manner heretofore described and under the automatic control of the conditions in the enclosure 10 and in varying the air modifying intensity or power of the apparatus. To this end, a snap acting wet bulb thermostat (or relative humidity hydrostat) 30 and a snap acting dry bulb thermostat 31 may be placed in any position to be affected by the general condition of the air in the enclosure 10. These controls are connected to the air conditioning mechanism to vary the operation thereof in order to maintain the proper conditions in the enclosure. Thus the dry bulb thermostat 31 varies, at times, the air modifying intensity or power of the units 11 and 12. To accomplish this, it controls the motor 32 which drives the compressor 25 and causes it to start and stop, which in turn varies the cooling power of the units 11

and 12 in a manner to tend to maintain the dry bulb in the enclosure 10 within predetermined limits. The wet bulb thermostat 30, which is responsive to humidity conditions in the enclosure, 5 may also vary the air modifying intensity of the units 11 and 12 and is therefore also connected to the motor 32 to cause the compressor 25 to operate and tend to maintain the relative humidity conditions in the enclosure 10 below a 10 predetermined limit. The compressor 25 is caused to operate whenever the arm 34 contacts at 35a in response to an increase in the wet bulb temperature in the enclosure 10. The controls 30 and 31 are in parallel electrical connection with 15 the motor 32, and either one of the controls can cause the motor to operate, and the motor will continue to operate so long as either control maintains the circuit closed. Thus the compressor 25 operates so long as either the dry bulb 20 or the wet bulb temperature is above its respective predetermined maximum limit, and tends to reduce either temperature below its said maximum limit.

In addition, the wet bulb thermostat 30 controls the nature of the flow of air through or past the units 11 and 12 to modify the dehydrating capacity of the apparatus. Preferably the flow of the stream of air is such that it has a substantially constant volumetric capacity 30 through the air conditioning apparatus, and the length of contact between portions of said stream and the combined cooling surface or zone of units 11 and 12 is varied to produce the necessary dehydrating action on the stream. In general, 35 when the nature of the contact is longer, as when the stream flows wholly or largely in series through the units 11 and 12, the dehydrating action is greater; and, conversely, when the nature of the flow is wholly or largely in parallel, the dehydrating action is decreased. Thus by 40 varying the nature of the air flow through the units 11 and 12 in accordance with the humidity conditions in the enclosure 10, the humidity conditions can be controlled or maintained within desired or predetermined limits. To this end, 45 the wet bulb thermostat 30 controls the dampers 13, 14, 15 and 16 and causes them to assume the various positions indicated in full and dotted lines in response to wet bulb temperatures in 50 the enclosure 10. In one embodiment, the dampers are mounted on hinged rods 40 which are placed under the tension of springs 41 and 42 which exert oppositely directed torsional forces on the rod 40 which are balanced when the 55 dampers assume the position indicated at *a* in Fig. 1. This may be called the intermediate or normal position of operations. A motor 43 is provided to actuate the dampers 13 and 15 and a motor 44 is provided to actuate the dampers 14 and 16 from the normal position. When 60 the wet bulb temperature falls to, or below, a predetermined limit, the arm 34 contacts at 36 and closes an electrical circuit leading to the motors 43 and 44 and causes the dampers to 65 assume the position indicated at *b*, causing the air to flow in a parallel relationship with respect to the units 11 and 12. When the air flows in this parallel relationship, the coils produce the minimum or lesser amount of dehydration of 70 the air, since the various portions of the air stream remain the shortest possible length of time in contact with a cooling surface. Thus a relatively large amount of air is cooled, but not to as low a temperature as when a larger series 75 flow is produced. It is to be understood that,

under these conditions, the compressor 25 may or may not be operating depending on the dry bulb conditions. If the dry bulb temperature in enclosure 10 is sufficiently low, the compressor does not operate, and if too high, it does operate. On the other hand, if the wet bulb temperature is at, or above, the upper desired or predetermined limit, the arm 34 contacts at 35a, and the compressor 25 is caused to operate, if it is not already operating under the control of dry bulb thermostat 31. In addition, the arm 34 contacts at 35 and the dampers assume the position indicated in full lines in Fig. 1 because the motors 43 and 44 are energized to turn in the necessary direction and this causes the maximum amount of series flow in the air stream. Under such conditions, all, or a certain portion, of the air is contacted for the maximum length of time with the cooling surfaces and this dehumidifies the air to the maximum extent and tends to reduce the wet bulb temperature or maintain it below a predetermined maximum limit in the enclosure 10.

The motors 43 and 44 may be of the "stall" type. When the dampers reach the limit of their movement, the motors stall and maintain the dampers at such limit positions as long as the motors are energized, but when the motors are de-energized, by the breaking of the contact at the wet bulb thermostat 30, then these springs 41 and 42 return the dampers to the position indicated at *a* which is an intermediate position. The drive or gear connection between the motors 43 and 44 and the rods 40 may be of any type which permits the motors to overcome the 30 springs as long as the motors are energized, but permit the springs to return the dampers to the position *a* when the motors are de-energized. This can be accomplished either by a proper mutual drive gear relationship between the motor and the rod, causing the motors to stall at 40 the end of the movement, or it may be accomplished by a slip clutch drive, (magnetic or otherwise) which has a greater power than the springs 41 and 42 while the motor is operating, (in which case the motors continue to turn until de-energized) and permits the return of the dampers when the motors are not energized. 45

Any means for causing a flow of air past the air modifying zones 11 and 12 may be provided. This may take the form of a fan 50, driven by 50 the motor 51 to produce a substantially constant volumetric flow of air through the air conditioning apparatus. The intake of the fan may be connected to a chamber 52 which in turn is supplied with outside fresh air through the conduit 53 and is supplied with air from the enclosure 10 through the conduit 54. The air thus enters into the chamber 52, enters the fan 50 and is caused to flow through the air conditioning apparatus contained in the casing 55 and is discharged into the enclosure 10.

A permanent air-by-pass 60 may be provided around the air modifying units 11 and 12. This by-pass 60 may be of any desired size, and preferably is of sufficient size to temper the air conditioned by the units 11 and 12 to prevent undesirable cold drafts in the enclosure 10. This by-pass is preferably never changed as to size and as to the volume of air flowing therethrough. 70 Thus a stop 61 is provided for damper 14 to prevent it from modifying the size of the by-pass. When the dampers are in position *a* dampers 16 and 14 are substantially parallel, but when they are in position *b* damper 14 is prevented from 75

turning by stop 61. A lost motion 62 is provided in the linkage 63 between dampers 14 and 16 through which motor 44 drives damper 14 to permit this converging position between these 5 two dampers. When these dampers are in position b their converging position tends to compensate for the decreased air resistance through the units due to the parallel air flow and thus tends to maintain a fixed ratio of air flow 10 through the units 11 and 12 and the by-pass 60. The dampers 13 and 15 are provided with a similar linkage 64 and lost motion 65, for turning damper 15 by motor 43, and with a stop 66 which aids in compensating for the varying air 15 resistance at various damper positions and tends to maintain a fixed ratio of volumetric flow between the by-pass 60 and the units 11 and 12.

While the form of embodiment of the invention as herein disclosed, constitutes a preferred form, it is to be understood that other forms might be adopted, all coming within the scope of the claims which follow.

What is claimed is as follows:

1. An air conditioning apparatus comprising 25 two or more air modifying units, means for causing a stream of air to pass selectively in series or parallel through said units to vary the effect upon the relative humidity of said air.

2. An air conditioning apparatus comprising 30 two or more air modifying units, means for causing a stream of air to pass through said units with a portion of said stream passing in series and another portion passing in parallel, and means for varying the ratio of said portions to 35 vary the effect upon the relative humidity of said air.

3. The method of conditioning air in an enclosure which comprises flowing a stream of air 40 through a plurality of air modifying zones and into said enclosure with a portion of said stream flowing through said zones in series and another portion in parallel.

4. The method of conditioning air in an enclosure which comprises flowing a stream of air 45 through a plurality of air modifying zones and into said enclosure with a portion of said stream flowing through said zones in series and another portion in parallel, and varying the ratio of said portions in accordance with conditions in said enclosure.

5. The method of conditioning air which comprises flowing a stream of air through a plurality 50 of air cooling zones with a portion of said stream flowing through said zones in series and another portion in parallel.

6. The method of conditioning air in an enclosure which comprises flowing a stream of air through a plurality of air cooling zones and into 60 said enclosure with a portion of said stream flowing through said zones in series and another portion in parallel, and varying the ratio of said portions in accordance with conditions in said enclosure.

7. An air conditioning system comprising, in 65 combination, a heat absorber, the main function of which is to remove principally sensible heat from air flowing thereover, a second heat absorber adapted to cool air flowing thereover to

below the dew point thereof, means responsive to the temperature of the air to be conditioned for controlling the heat exchange between the air and said absorbers, means for controlling the flow of air over the second mentioned heat absorber, and means responsive to the relative humidity of the air to be conditioned for actuating the controlling means.

8. An air conditioning system comprising, in combination, a heat absorber, the main function 10 of which is to remove principally sensible heat from air flowing thereover, a second heat absorber adapted to cool at least a part of said air to below the dew point thereof, means responsive to the temperature of the air to be conditioned 15 for controlling the heat exchange between the air and said absorbers, means for controlling the flow of air over the second mentioned heat absorber, and means responsive to the relative humidity of the air to be conditioned for actuating 20 the controlling means.

9. An air conditioning system comprising, in combination, refrigerating apparatus including an evaporator, the main function of which is to remove principally sensible heat from air flowing 25 thereover, a second evaporator adapted to cool air flowing thereover to below the dew point thereof, means for withdrawing gaseous refrigerant from the evaporators and for condensing the refrigerant and for delivering the same to said 30 evaporators, means responsive to the temperature of the air to be conditioned for controlling the refrigerating apparatus, means for controlling the flow of air over the second mentioned evaporator, and means responsive to the relative humidity of the air to be conditioned for actuating 35 the second mentioned controlling means.

10. An air conditioning system comprising, in combination, refrigerating apparatus including an evaporator, the main function of which is to remove principally sensible heat from air flowing 40 thereover, a second evaporator adapted to cool at least a part of said air to below the dew point thereof, means for withdrawing gaseous refrigerant from the evaporators and for condensing the refrigerant and for delivering the same to said 45 evaporators, means responsive to the temperature of the air to be conditioned for controlling the refrigerating apparatus, means for controlling the flow of air over the second mentioned evaporator, and means responsive to the relative humidity of the air to be conditioned for actuating 50 the second mentioned controlling means.

11. An air conditioning system comprising, in combination, refrigerating apparatus including 55 an evaporator, the main function of which is to remove principally sensible heat from air flowing thereover, a second evaporator adapted to cool at least a part of said air to below the dew point thereof, means for withdrawing gaseous 60 refrigerant from the evaporators and for condensing the refrigerant and for delivering the same to said evaporators, means for controlling the flow of air over the second mentioned evaporator, and means responsive to the relative humidity of the air to be conditioned for actuating 65 the controlling means.
